UNITED STATES PATENT OFFICE

167,961

DECK OF PLAYING CARDS

Etienne L. Vervuurt, Caracas, Venezuela

Application April 29, 1952, Serial No. 19,520

Term of patent 7 years

(Cl. D34—13)

To all whom it may concern:

Be it known that I, Etienne L. Vervuurt, a citizen of the Netherlands, residing at Caracas, in Departamento Libertador, Distrito Federal, Venezuela, have invented a new, original, and ornamental Design for a Deck of Playing Cards, of which the following is a specification, reference being had to the accompanying drawings, forming part thereof, in which

Fig. 1 is a face view of each one of twenty-four cards in a deck of playing cards, showing my new design;

Fig. 2 is a face view of each one of twenty-four other cards in the deck; and

Fig. 3 is a face view of each one of four remaining cards in the deck.

The cards are of no appreciable thickness and the backs of the cards are conventional.

The dominant features of my new design are shown in solid lines in the drawings.

I claim:

The ornamental design for a deck of playing cards, as shown and described.

ETIENNE L. VERVUURT.
